THERMOCOUPLE PROBE

Alf Hundere, 2905 Bandera Road, San Antonio, Tex.

Filed June 1, 1964, Ser. No. 80,229

Term of patent 14 years

(Cl. D26—1)

FIGURE 1 is a side elevational view of a thermocouple probe, showing my new design, the appearance being the same from all sides;

FIGURE 2 is an end elevational view looking in the direction of the arrows 2—2; and

FIGURE 3 is an end elevational view looking in the direction of the arrows 3—3.

I claim:

The ornamental design for a thermocouple probe, as shown and described.
